[57] CLAIM

The ornamental design for a combined electric iron support and steam generator, as shown.

DESCRIPTION

FIG. 1 is a top, front and side perspective view of a combined electronic iron support and steam generator, showing my new design;

FIG. 2 is a front elevational view thereof;

FIG. 3 is a rear elevational view thereof;

FIG. 4 is a side elevational view thereof as seen from the right of FIG. 2;

FIG. 5 is a side elevational view thereof as seen from the left of FIG. 2;

FIG. 6 is a top plan view thereof; and

FIG. 7 is a bottom plan view thereof.
